UNITED STATES PATENT OFFICE.

ROBERT Y. BARROWS, DECEASED, LATE OF RUTHERFORD, NEW JERSEY; BY GRACE A. BARROWS, ADMINISTRATRIX, OF RUTHERFORD, NEW JERSEY.

DESIGN FOR A PHONOGRAPH CABINET.

Application filed December 26, 1923. Serial No. 8,152. Term of patent 14 years.

To all whom it may concern:

Be it known that ROBERT Y. BARROWS, late a citizen of the United States, and formerly residing at Rutherford, county of Bergen, and State of New Jersey, deceased (Grace A. Barrows, of Rutherford, N. J., administratrix of the estate of Robert Y. Barrows, deceased), did during his lifetime invent a new, original, and ornamental Design for Phonograph Cabinets, and I, the administratrix, do hereby declare the following to be a true specification of said design, reference being had to the accompanying drawings, forming a part thereof.

In the drawing:

The figure is a perspective view showing the cabinet closed.

I claim:

The ornamental design for a phonograph cabinet as shown.

GRACE A. BARROWS,
Administratrix of the estate of Robert Y. Barrows, deceased.
